US00D592401S

(12) **United States Design Patent**
Beavers et al.

(10) **Patent No.:** **US D592,401 S**
(45) **Date of Patent:** **** May 19, 2009**

(54) **CONTAINER**

(75) Inventors: **Brooke Beavers**, Dallas, TX (US); **Lynn Phillips**, Bedford, TX (US); **Bruce Teitelbaum**, New York, NY (US)

(73) Assignee: **Mary Kay Inc.**, Dallas, TX (US)

(**) Term: **14 Years**

(21) Appl. No.: **29/297,873**

(22) Filed: **Nov. 20, 2007**

(51) LOC (9) Cl. **03-01**

(52) U.S. Cl. **D3/304**

(58) Field of Classification Search D3/200, D3/201, 203.1, 203.3, 205–206, 273, 276, D3/304–315; D6/525, 475–476; D19/75, D19/77, 86, 90, 92, 100; 206/203, 214–215, 206/822, 307.1; 229/100, 914, 913, 406

See application file for complete search history.

CLAIM

The ornamental design for a container, as shown and described.

DESCRIPTION

FIG. 1 is a top front perspective view of our design;

FIG. 2 is a right side view of the design;

FIG. 3 is a left side view of the design;

FIG. 4 is a front view of the design;

FIG. 5 is a back view of the design; and,

FIG. 6 is a top view of the design.

The broken lines in the figure views depict environmental structure and portions of the container that form no part of the claimed design.
